UNITED STATES PATENT OFFICE.

CHRISTIAN GRAFF, OF UPPER ST. CLAIR, PENNSYLVANIA.

LOCK FOR MILK-CANS.

SPECIFICATION forming part of Letters Patent No. 284,412, dated September 4, 1883.

Application filed June 26, 1883. (No model.)

To all whom it may concern:

Be it known that I, CHRISTIAN GRAFF, a citizen of the United States, residing at Upper St. Clair, in the county of Allegheny and State of Pennsylvania, have invented new and useful Improvements in Locks for Milk-Cans, &c., of which the following is a specification.

My invention relates to the construction of locks, and especially such locks which are used for securing the lids of milk-cans during transportation from the farmer to the dealer.

The object of my invention is to produce a lock which is simple in its construction and operation without being unsafe, and which is entirely independent of the can-lid, thus leaving the lid plain or free of incumbrances, to which end it consists in the novel construction and arrangement of parts hereinafter described, and illustrated in the accompanying drawings, in which—

Figure 1 is a face view of the lock applied to a can. Fig. 2 is an end view thereof. Fig. 3 is a sectional front view on a larger scale than in the previous figures. Fig. 4 is an end view on a similar scale to Fig. 3. Fig. 5 is a cross-section on the line *a a*, Fig. 3.

Similar letters indicate corresponding parts.

The letter A designates the lock-case, which is permanently secured to the can-body B in proper relation to its lid C. In this case A is arranged a bolt, D, which projects through and beyond the case at one end, where it is provided with a laterally-projecting hook, E, and with a head, F, of square or polygonal shape, the latter being at the inner end of the hook. On the inner portion of the bolt D is coiled a spring, G, which acts thereon with a tendency to impel or force it outward from the lock-case, while in the bolt is formed a recess, H, adapted to receive a tumbler, I. This tumbler I is provided with a locking spring, J, and is arranged to be retracted by

a dog, K, which is operated by a suitable key, or which may form the bit of the key. On the end of the lock-case through which the bolt 45 passes is a boss, L, which is square, like the bolt-head F, and forms a socket to receive such head when the bolt is locked; but, if desired, this boss may be omitted and the socket formed by the hole in said end of the lock-case. 50

In applying the lock to use the tumbler I is retracted, so as to release the bolt D, when the latter shoots outward under the impulse of the spring G a sufficient distance to enable the bolt-head F to clear the socket L. The bolt D is then turned in the proper direction to cause its hook E to catch over the edge of the can-lid, when it is forced inward against the action of the spring G until the tumbler re-engages the bolt. In this manner the bolt-head F is brought into the socket L, and, due to the shape of the head and socket, the bolt is thereby effectually prevented from turning, while by the tumbler the bolt is firmly held against longitudinal movement, and hence the 65 hook is properly locked.

It is evident that my lock can be applied to other vessels besides milk-cans.

What I claim as new, and desire to secure by Letters Patent, is— 70

The bolt having one end provided with a laterally-projecting hook and with a square or polygonal head, in combination with the lock-case having a socket to receive the bolt-head, the bolt-impelling spring, and the tumbler 75 adapted to engage the bolt, substantially as and for the purpose described.

In testimony whereof I have hereunto set my hand and seal in the presence of two subscribing witnesses.

CHRISTIAN GRAFF. [L. S.]
